UNITED STATES PATENT OFFICE.

BERNARD BIEHL, SR., OF NEWARK, NEW JERSEY, ASSIGNOR TO J. L. SOMMER MANUFACTURING CO., A CORPORATION OF NEW JERSEY.

DESIGN FOR A MILK-BOTTLE OPENER.

60,009.

Specification for Design.

Patented Dec. 20, 1921.

Application filed July 23, 1921. Serial No. 487,198. Term of patent 14 years.

To all whom it may concern:

Be it known that I, BERNARD BIEHL, Sr., a citizen of the United States, residing at Newark, in the county of Essex and State of New Jersey, have invented a new, original, and ornamental Design for a Milk-Bottle Opener, of which the following is a specification, reference being had to the accompanying drawing, forming part thereof.

Figure 1 is a side view showing a milk bottle opener of my design;

Fig. 2 is a front edge view of the same, and

Fig. 3 is a bottom view.

I claim:

The ornamental design for a milk bottle opener, as shown.

BERNARD BIEHL, SR.
